APPARATUS FOR MIXING PAINT

Myron D. McCauley, Huntington Woods, Mich.,
assignor to Rinshed-Mason Company, Detroit,
Mich., a corporation of Michigan

Application November 18, 1946, Serial No. 710,503

6 Claims. (Cl. 33—126.7)

1

This invention relates to an apparatus for mixing two or more liquids to obtain desired results in the mixture and it has to do particularly with the mixing of such materials as paints, lacquers, varnish, shellac, or other preparations, such as an oil.

More particularly, the invention is directed to the provision of an apparatus for mixing a plurality of paints or the like together to obtain certain colors or shades. For convenience and brevity, the disclosure will be made with reference to paint, this term being used in a broad sense to cover the various ingredients. With the use of the apparatus a job shop may carry a limited number of base colors and by mixing these colors in prescribed quantities, various colors and shades may be obtained. Thus, a job shop is equipped to repair or refinish automobiles or parts thereof having a wide variety of colors and shades, by having in stock only a few of the base colors.

The general object of the invention is the provision of an improved mechanism by means of which specified quantities of paints may be placed in a vessel to obtain the desired color. To this end, an improved mechanism is provided. It is also an object of the invention to provide an improved gauging device, by means of which the level of the liquid in the container may be accurately ascertained. The gauge resides basically in the illumination of the surface of the paint which is being poured or otherwise placed into the vessel and visually ascertaining the level. This is accomplished by an arrangement which combines an arrangement for illuminating the surface of the liquid with means for directing the reflected light from the surface of the liquid to a location where the operator may easily see the same. To this end, a periscope arrangement is provided.

Another object is to provide an apparatus which is quickly and easily operable to adjusted positions and to this end, power driving means is preferably provided for shifting the position of the liquid level gauge. In conjunction with this, a manually operable adjusting means is provided for obtaining an accurate setting following a general setting of the gauge by the power means.

Other objects of the invention will become apparent as the detailed description is followed in conjunction with the accompanying drawings:

Fig. 1 is a view of a device constructed in accordance with the invention showing the same in partial side elevation and with parts cut away and with parts in section.

Fig. 2 is an enlarged cross sectional view taken

2

substantially on line 2—2 of Fig. 1 illustrating an operable element.

Fig. 3 is a sectional view taken substantially on line 3—3 of Fig. 1 showing a counter arrangement.

Fig. 4 is a plan view of the apparatus showing some of the concealed parts in dotted lines.

Fig. 5 is an enlarged cross sectional view taken substantially on line 5—5 of Fig. 4 showing the manual control for setting the indicator.

Fig. 6 is an enlarged cross sectional view of the gauging element showing the wiring and the electric lamps.

Fig. 7 is a cross sectional view taken substantially on line 7—7 of Fig. 6 showing some of the structure in the head of the gauging element.

Fig. 8 is a cross sectional view taken substantially on line 8—8 of Fig. 6 showing the tube structure of the gauging element.

Fig. 9 is a diagrammatic view illustrating the field visible by an operator.

Fig. 10 is an enlarged cross sectional view taken substantially on line 10—10 of Fig. 1 showing the operating structure.

Fig. 11 is an enlarged cross sectional view taken on line 11—11 of Fig. 10 showing the structure of the post and operating guide.

Figure 12 is a view illustrating the electrical wiring diagram.

As illustrated in Figs. 1 and 2, the apparatus comprises a base in the form of a housing 1 having a lower closure plate 2. The housing has a supporting portion 3 and an extending portion 4. Secured to the housing at its mid-point is a post or standard 6.

The supporting surface 3 is designed to receive a vessel such as a paint can 7 and for positioning the can there is preferably provided an arcuate abutment 8 against which the can may be placed. A gravity switch, advantageously of the mercury bulb type, illustrated at 9, is pivotally mounted as at 10 and it has a trigger or finger 11 arranged to be engaged by a can to swing the bulb 9 into an angular position for making an electrical circuit for purposes which will presently appear.

Mounted in the post 6 is a screw 15 which seats upon the lower portion of the post and takes a bearing in a bracket 16. The upper end of the post (Figs. 10 and 11) is provided with a head 17. This head is cut away to receive, slidably, a split tube 18 which is engaged by spaced bearing portions 19 in the head. The head is cut away for the reception of a supporting piece 20 having a partially circular part 21 fitting

within the split tube and which is secured to the head of the post as by means of a screw 22. The portion 21 of the element 20 has a central opening therein, in which the upper end of the screw 15 is journaled as at 23. Secured to the lower end of the split tube is a nut 25 which is threaded onto the screw 15.

The screw is an operating element for raising and lowering the split tube 18 and for this purpose the structure shown in Fig. 1 is provided with a bevelled gear 26 secured to the bottom of the screw. A driving shaft 27 journaled in the bracket 16 has a bevel gear 28, the teeth of which mesh with those of the gear 26. The shaft 27 is preferably power driven and for this purpose it is journaled in spaced brackets 30 and 31 and provided with a worm gear 32. A small reversible electric motor 35 has a shaft 36 provided with a worm 37 for operating the gear 32 as illustrated in Fig. 5. It will be seen that operation of the motor will effect rotation of the screw 15 through the mechanism just described.

A hand set arrangement, as illustrated in Fig. 5, takes the form of a clutch member 40 secured to the motor shaft and a clutch member 41 mounted on a shaft 42 which extends out through the housing and is provided with a hand operated turning instrument such as a knoblike device 43. A spring 44 which acts upon an abutment 45 and reacts against a bracket 46 normally holds the clutch member 41 retracted away from the clutch member 40 but pressure on the piece 43 may shift the shaft 42 and the clutch member 41 to the right as Fig. 5 is viewed, to cause engagement with the clutch member 40 so that if the hand piece 43 is turned, the worm 37 is operated to thus turn the screw 15.

An indicator system in the form of several counter mechanisms, is disposed in the extension 4. As shown in Fig. 1, the shaft 27 is extended and is journaled in a bracket 50 and mounted above the same are a plurality of indicators A, B, C and D, each driven by gears on the extension of the shaft 27 as shown at 51, 52, 53 and 54. These counters are arranged for different sizes of receptacles 7 and, as indicated in Fig. 4, the counters are respectively for containers of pint, quart, one-half gallon and gallon capacity, there being preferably suitable indicia on the housing 4 to indicate the same as shown. The top of the housing extension 4 is provided with a slot 56 for exposing the numerals on the counters and mounted just under the slot is a shield 57 pivotally journaled on the axis of the counters as shown at 58 (Figs. 2 and 3). This shield is arcuate in formation and is provided with a number of apertures 59 so that rotary adjustment of the shield exposes the elected counter. To shift the shield the same is provided with a thumb piece 60 which is engageable through an opening 61 in the housing. A detent arrangement in the form of an arm 62 having a spring-pressed ball is associated with the operating finger piece 60 and the spring-pressed ball is engageable in recesses 63 in the bracket 50. As shown in Fig. 4, the several openings 59 are circumferentially offset, there being one for each counter and adjustment of the finger piece 60 aligns an opening 59 with an elected counter to expose the same while concealing the other counters.

Mounted on top of the split sleeve 18 is a head 70 for carrying the gauging element generally indicated at 71. A plate of insulating material 72 supports depending rods 73 which extend into

tubes 74. Each tube has its lower end extending through the surface member 4 of the housing and insulated therefrom by insulation 75 and has its upper end disposed in the plate 17 and insulated therefrom by a bushing 78. For holding each tube in place, each tube has a washer 76 adjacent its lower end and a washer 77 adjacent its upper end, these washers being secured to the tube and lying between the bushings 75 and 78. The rods 73 thus engage the tubes to provide an electrical connection and the rods are slidable in the tubes. To maintain a good contact the distance between the locations of connections of the rods to the plate 12 is a little different, such, for example, a little greater than the distance between the locations of mounting of the tubes 74 so that the rods are slightly flexed to thus maintain a wiping contact with the interior of the tubes.

The head 70 overhangs the location of reception of the vessel 7 and supports a depending gauging element. This element is in the form of a flattened exterior tube 72, the upper end of which is fitted in the head as shown in Fig. 6 and within this exterior tube are three other tubes 73, 74 and 75. The exterior tube and the interior tube 74 may be held to the head by means of a screw 76 while the tubes 73 and 75 may be held positioned by screws 77.

The lower end of each of the tubes 73 and 75 is equipped with a socket 80 for the reception of an electric bulb 81. These bulbs are positioned somewhat above the lower end of the exterior tube 72. The interior tube 74 projects downwardly beyond the lower ends of the tubes 73 and 75 and the interior tube is fastened so that its shape gradually changes to an elongated or oval form so that its lower end 83 is of somewhat oval shape as shown in Fig. 8. The lower end of the tube 74 projects beyond the lower end of the exterior tube 70 and positioned on opposite sides thereof are lenses or prisms 85. These lenses or prisms are relatively permanently positioned to seal the lower end of the tube 72 and the lower end of the tube 74 is closed by means of a transparent piece 86. The prisms and the piece 86 are preferably of glass so as to not be deleteriously affected by the paint or lacquer with which the same are to be used. Where liquids are to be gauged which do not attack plastic, transparent plastic elements may be employed.

The tube 74 is, in effect, a periscope tube and mirrors or reflecting elements are used in the head 70. One mirror is shown at 87 and another at 88. A sight line down the center of the tube is illustrated at 89 while the eye of an observer is diagrammatically illustrated at 90.

The electrical diagram illustrated in Fig. 12 shows a switch box 91 mounted inside the housing with an operating lever 92 projecting through the housing. Conductors form a source of electrical current, such as the usual 110 A. C. are shown at 93 and 94. One conductor leads to the switch 91, another extends to a terminal for the reversible electric motor 35. Also connecting the switch and the motor are three other electrical conductors 95, 96, and 97. The electrical set up is not shown in detail as this arrangement is known to those skilled in the art. Suffice it to say, that the switch arm 92 is operable to one dotted line position for the operation of the motor 35 in one direction, and to the other dotted line position, shown in Fig. 12, for the operation of the motor in the opposite direction, while it

is in its full line position, as shown in Fig. 12, no current is supplied to the motor.

Conductors 100 and 101 extend from the power lines 93 and 94 to a transformer 102 located in the housing. Extending from the transformer are two conductors 103 and 104 for carrying a reduced voltage such, for example, as six or eight volts. One conductor extends directly to and is connected to one of the tubes 74 (Fig. 10), while the other conductor 103 runs through the mercury switch 9 and then connects to the other conductor tube 74. In the head 70 are conductors 106 and 107 for carrying current to one bulb 81 and conductors 108 and 109 for carrying current to the other electric bulb 81. These conductors extend downwardly through the tubes 73 and 74 and conveniently being in the form of a double conductor wire as shown in Fig. 6, the double conductor wires being illustrated at 110 and 111.

In the operation of the device, a can of selected size, such as a quart, is placed upon the platform as indicated in Fig. 1. This is done when the gauge is in an elevated position. The gauge is now lowered until its lower end rests upon the bottom of the can at which time the indicators all read zero. The shield 57 is adjusted to show the counter which corresponds to the selected container such as the quart, suggested above. A given quantity of thinner may be placed in the bottom of the can preliminarily and the arrangement is such that when the gauging element is properly adjusted with relation to the surface of the thinner, the counters read zero.

An advantageous and preferable arrangement is to so construct the counter as to divide the receptacle into 1000 parts, or, in other words, 999 indications on the counter. Let an arbitrary situation be assumed where a paint mix is to be provided which comprises 100 parts of white, 400 parts of blue, and 500 parts of yellow. The driving motor is now operated to turn the screw and elevate the gauging element. The element is to be elevated until the counter indicates 100, this showing that the space below the counter equals 100 parts out of the total of 1000 in the container. After the motor has driven the gauge upwardly and it is stopped as near as a reading of 100 as possible, the final accurate adjustment may be made by the operator pressing the button 43 and turning the same to arrive at the accurate reading by the indicator. The operator gazes into the periscope tube as indicated in Fig. 6, the rays of light from the lamps 81 pass through the prisms and are bent as generally indicated by the lines 115 and 116 in Fig. 6 so that the rays cross each other. This point of crossing is preferably substantially centrally disposed at a point below the transparent closure 86. The light shines upon the surface of the paint as indicated and the light is reflected up through the tube 74 and it can be seen by the observer employing the reflecting mirrors. The pouring is continued while the operator watches the reflected light through the periscope tube. The illuminated field visible through the periscope will have an area and shape substantially corresponding to the shape of the lower end of the periscope tube as indicated by the area 117, Fig. 9. As the level of the paint rises, say from the level indicated at x , Fig. 6, there is substantially no change in the appearance through the periscope tube until the level of the paint rises above the point of intersection of the rays. When the level of the paint, for example, is about at the level y , there are no light rays played directly upon the surface which lies between the

diverging beams from the two lamps. Therefore, a dark streak 118 will appear on the visible area as shown in Fig. 9. This is an indication to the operator to be careful in the pouring of the paint as the level is approaching the level for which the gauge was set. As the surface of the paint rises, from the level y , the darkened streak 118 gradually widens and finally, when the level of the paint reaches the lower end of the periscope tube the light is cut off and none is transmitted upwardly through the periscope tube. This level of the paint is indicated at z in Fig. 1. At this precise point, the pouring of the paint in the can is stopped and 100 parts of white paint has been supplied. The motor is now operated until the counter shows 500, thus indicating that it has been elevated 400 points and the blue paint is now poured into the can. When the level reaches the depending end of the periscope tube all light is cut off and it is then known that 400 parts of blue have been added. The gauge is next elevated to provide the 500 parts of yellow and the steps are repeated.

The vessel is now full of a proper mixture of basic colors which, when properly mixed provides the desired color or shade. If a pint, one-half gallon, or gallon of paint is desired the appropriate counter is used. In the event, one of the light bulbs becomes defective in use, the outer tube 72 may be released by its holding screw and slipped from the head 70. This exposes the bulb so that it may be replaced.

After the can has thus been filled and removed, the gauge may be lowered by reverse operation by the electric motor. On the other hand, the gauge may not be lowered until the next use of the apparatus at which time a can will be located on the platform so that the gauge may be lowered into the same. And, it is to be pointed out at this time, that, when not in use, the circuit through the lamps is broken by the mercury switch 9, inasmuch as the switch is closed only when a can is properly positioned on the platform.

It will be seen from the above that the arrangement provides for a very accurate gauging of paint to be placed into a vessel. The operator receives a warning when the level of the paint is approaching the level for which the gauge is set by the appearance of the dark streak across the visible area. From this point on the operator may be particularly careful in pouring the paint into the receptacle. When the level of the paint contacts with and shuts off light from entering the closure 86, the interior of the vessel remains illuminated. This is because the light passes out through the prisms 85 which, in a normal and proper use, remain above the paint level. By initially pouring a small amount of thinner in a can this thinner floats upon the surface of the paint and prevents the pigment in the paint from discoloring the prisms and the closure piece 86. Thus, after paint has been poured into the vessel up to the desired indicated level the operator may, for any purpose whatever, inspect the interior of the can which remains illuminated.

I claim:

1. An apparatus for determining the level of the surface of a liquid in a vessel, comprising a gauging member, means for adjustably shifting the gauging member vertically so that the same may be projected downwardly into a vessel, means for indicating the vertical position thereof, a light source carried by the member for illuminating the surface thereof, an element for conducting upwardly light rays which are reflected from

the surface of the liquid, lens means for directing rays from the light source diagonally across the lower end of the light conducting element, said lower end of the light conducting element adapted to be engaged by the liquid to cut off reflected light.

2. An apparatus for determining the level of the surface of a liquid in a vessel, comprising a tube projectable vertically into the vessel, a light source near the bottom of the tube for illuminating the surface of the liquid, an element within the tube for conducting upwardly light rays reflected from the surface of the liquid and which are visible to an operator, the lower end of the element projecting downwardly below the light source, lens means for directing rays from the light source diagonally across the lower end of said element, the lower end of the element adapted to be engaged by the liquid to cut off reflected light and means for indicating the position of the lower end of the element relative to the vessel.

3. An apparatus for determining the level of the surface of a liquid in a vessel comprising, a support projectable downwardly into a vessel, a pair of light sources for illuminating the surface of the liquid, a light conducting element positioned between the light sources for conducting upwardly light reflected by the liquid and which may be viewed by an operator, the lower end of the light projecting element extending below the light sources, lens means for directing the light beams from the sources so that the light beams diagonally cross at a point below the lower end of the light conducting element, whereby when the level of the liquid is above the point of the crossing of the light beams the same is indicated by a dark area in the visible field, the lower end of the element adapted to be engaged by the liquid to cut off reflected light and means for indicating the position of the lower end of the light conducting element relative to the vessel.

4. A gauging element for determining the level of the surface of a liquid in a vessel comprising, an outer tube member, means for projecting the tubular member downwardly into a vessel and for indicating its vertical position relative to the vessel, a pair of spaced tubes positioned within the outer tube, an electric lamp carried by each of said spaced tubes in a location above the bottom of the outer tube, a light conducting tube within the outer tube and positioned between the electric lamps, the lower end of the light conducting tube projecting below the outer tube, said light conducting tube conducting upwardly light reflected from the surface of the liquid to be viewed by an operator, a lens for each electric lamp, said lenses arranged to direct the light rays from the lamps diagonally so that the light rays from the respective lamps cross each other at a point below the light conducting tube.

5. A gauging element for determining the level of the surface of a liquid in a vessel comprising, an outer tube member, means for projecting the tubular member downwardly into a vessel and for indicating its vertical position relative to the vessel, a pair of spaced tubes positioned within the outer tube, an electric lamp carried by each of said spaced tubes in a location above the bottom of the outer tube, a light conducting tube within the outer tube and positioned between the electric lamps, the lower end of the light conducting tube projecting below the outer tube, said light conducting tube conducting upwardly light reflected from the surface of the liquid to be viewed by an operator, a lens for each electric lamp, said lenses arranged to direct the light rays from the respective lamps cross each other at a point below the light conducting tube, and a transparent closure piece for the lower end of the light conducting tube.

6. A gauging element for determining the level of the surface of a liquid in a vessel comprising, an outer tubular shell, means for projecting the tubular shell downwardly into a vessel and for indicating its vertical position relative to the vessel, said tubular shell being of relatively flattened construction, three tubes within the outer tube, one of which is disposed between the other two, an electric lamp carried by each of the outer tubes above the bottom of the tubular shell, the central tube extending below the tubular shell, the lower end of the central tube being of flattened construction, a lens on each side of the lower portion of the central tube for closing the lower end of the tubular shell, a transparent closure for the lower end of the central tube which is located below said lenses, said lenses being arranged to direct the light rays from the lamps diagonally downwardly so that the same cross each other below the lower end of the central tube, said central tube adapted to conduct upwardly light rays reflected from the surface of the liquid and being adapted to be engaged by the liquid to cut off the light rays conducted thereby.
